UNITED STATES PATENT OFFICE.

CLARK D. FISH, OF ANSONIA, CONNECTICUT.

COMBINED MACHINE FOR PRINTERS' USE.

SPECIFICATION forming part of Letters Patent No. 351,830, dated November 2, 1886.

Application filed April 11, 1884. Serial No. 127,466. (Model.)

To all whom it may concern:

Be it known that I, CLARK D. FISH, residing at Ansonia, in the county of New Haven and State of Connecticut, have invented certain new and useful Improvements in Combined Machines for Printers' Use; and I do declare the following to be a full, clear, and exact description of the same, reference being had to the accompanying drawings, which form a part of this specification.

My invention relates to an improvement in machines for printers' use, and more particularly to devices for incurvating leads and brass rules and for mitering the latter, the object being to produce improved means for the several purposes, and to combine such means in a single compact and convenient machine.

With these ends in view my invention consists in certain details of construction and combinations of parts, as will be hereinafter described, and pointed out in the claims.

In the accompanying drawings, Figure 1 is a view in perspective of a machine embodying my invention. Fig. 2 is a view in elevation from the opposite side of the machine. Fig. 3 is a view of the machine in vertical longitudinal section. Fig. 4 is a view thereof in vertical transverse section; and Fig. 5 is a detached view in horizontal section through the frame of the mitering-knife and the operating-lever, the outer end of the latter being broken away.

Inasmuch as these several devices for cutting, mitering, and incurvating embraced by this invention are separate and distinct mechanisms, they will first be so considered, and finally as embodied in a combined machine and operated from a common source of power.

With reference, at the outset, to cutting leads and rules, it is to be observed that while the former require a square cut the latter must be severed by a slanting or draw cut.

My improved cutting device comprehends cutting the leads and rules, as described, upon a common table and with the same knives.

This first part of the invention is shown in Figs. 1, 2, and 3 of the drawings, in which A is a knife having the outer portion of its cutting-edge made square and the inner portion thereof made inclined. The said knife operates in conjunction with a knife, B, having a

straight cutting-edge, and secured to one end of a table, C, mounted upon the base D of the machine, and divided into two working parts or faces by a central longitudinal ledge, E, the upper face of which is scaled to pica. In miters of this construction and arrangement of parts whatever is placed upon the outer part of the table and brought within range of the knives receives a square cut, while whatever is placed upon the inner part of the table is severed by a draw cut. Means are thus afforded for cutting both leads and rules upon a common table and with the same knives. The table is provided with a gage, F, having a slot, G, to fit over the ledge E aforesaid, and held in place by a beveled arm, H, depending from its inner end and embracing the beveled inner edge of the table, and by a screw, I, mounted in a slanting position in an arm, J, depending from the outer end of the gage and arranged to impinge obliquely against a shoulder, K, located beneath the outer edge of the table and running parallel therewith. The described arrangement of the screw causes the gage to be slightly twisted upon the table, as it were, and thereby firmly locked thereupon. Shoulders L and M, formed integral with the outer end of the gage, as shown, respectively prevent it from tipping and from being unduly deflected. In this they are re-enforced by the bearing obtained between the arm H and the inner edge of the table.

The knife A aforesaid is removably secured to a frame, N, provided with a bearing, O, working upon a face, P, located upon the base D of the machine, and having a rearwardly-extending arm, Q, provided with a sleeve, R, and fulcrumed to the base of the machine upon a stud, S, which passes through the said sleeve. A double link, T, connects the frame N with a lever, U, fulcrumed to the base of the machine, as shown, and normally held in an elevated position by a spring, V, engaging with its lower face. The actuation of the said lever for operating the knife A aforesaid will be described further on, where the several mechanisms are considered in their combined relation.

With reference, now, to the mitering mechanism, the mitering-knife W is mounted in a frame, X, supported upon, and reciprocated

for operating the knife by, an operating-lever, X, the rear end of which is provided with a yoke, Z, pivoted by a pin, A', to a bearing, B', having flat upper and lower faces, and 5 journalled upon a shaft, C', located in a shoulder, D', formed integral with the standard E' of the machine, the said bearing being held upon the shaft by means of a nut, F', as shown. The described mode of hanging the operating- 10 lever permits it to be moved vertically and laterally, as required, for operating the knife in mitering. It also permits the lever to be thrown outward for the removal of the frame X, or for other purposes. The said frame is 15 supported upon the lever by means of two parallel arms, G', which embrace it and its inwardly-projecting arm H', as represented. This arrangement for supporting the frame prevents it from perpendicular deflection, and 20 thus insures perfectly true cutting of the rules, whereby both edges are made available for printing. The frame is guided by an upright guide, I', secured to the base of the machine and rising above the mitering-table J', on a 25 line parallel with the working-edge K' thereof, and having its outer face convex to conform to the arc traversed by the frame when vertically reciprocated for the up and down strokes of the knife. The rear edge of the frame is 30 concaved on the same circle, and both edges are constructed and adapted to be interlocked, as shown in Fig. 5 of the drawings, in such manner as to permit the necessary lateral play of the frame. In order that the knife may 35 invariably cut on a true line, or, in other words, on a line parallel with the edge K' of the mitering-table, the inner face of the operating-lever is provided with a convex bearing, L', which engages with a flat bearing, M', located upon the outer face of the frame, and causes the same to swing into position with 40 the edge of the table upon the inward movement of the lever, preparatory to the down-stroke of the knife, which, with the frame, is deflected obliquely a little during its upstroke. If desired, the bearings L' and M' may be 45 reversed in position. The said knife is mounted upon a concaved plate, N', fulcrumed upon a ledge, O', located within the frame X, and operating, when the screw P' is turned down upon the knife, to force the edge thereof against the upper wall of the slot Q', located in the inner face, R', of the frame. The shavings removed by the knife pass through the said slot 50 to the chute S' of the frame, from which they are discharged clear of the machine. The mitering-table J' is provided with a rest, T', furnished with a gage, U', of ordinary construction. The present invention, so far as the 55 said table and rest are concerned, consists in providing the outer edge, V', of the former with holes W', located at the points of the mitering-angles, and in providing the latter with a pin, X', located in a concaved shoulder, Y', depending from it, and encircled by 60 a spring, Z', by which it is automatically projected into the holes when brought into opposition with them.

This arrangement, which takes the place of lines drawn upon the table, and a clamp for setting the rest, enables the same to be set quickly and with invariable accuracy. The rest is provided, as shown in Fig. 3 of the drawings, with a tapering web, A², extending from its inner end to the shoulder Y' aforesaid, with which it is cast integral. 75 This web affords a broad bearing for the rest, which it also strengthens.

Coming now to the incurvating mechanism, its leading feature is a segmental incurvator, B², having a bending-face, C², and provided with an upwardly-extending arm, D², which is connected by means of a thumb-screw, E², with a curved and slotted arm, F², attached to one side of the carriage G², and having its outer face scaled to gage the raising and lowering 85 of the incurvator for changing the inclination of the bending-face C², and consequently the degree of incurvation produced in the leads and rules. The inner face of the incurvator is provided with a curved lip, H², fitting into a groove, I², formed in the feed-roller J², and supporting the incurvator above the periphery of the roller J², which is roughened to feed the leads and rules to the bending-face C² aforesaid. The said roller is mounted upon a shaft, 90 K², journalled in the carriage G², which is hung between the arms L² of the standard E' by means of a pivot, M², located therein, as shown. The rear portion of the said carriage is concaved to conform to the outer surface of the incurvator, for which it forms a support and bearing. The leads and rules are held between the feed-roller above described and an anti-friction roller, N², journalled upon a removable pin, O², located in the outer ends of 95 the arms L², which serve as guides for the leads and rules. The object in making provision for the removal of the said anti-friction roller is to permit the leads and rules to be 100 removed after incurvation without being bent or distorted. The feed-roller is adjusted toward and from the anti-friction roller, as may be necessary, by means of a lever, P², extending through an aperture, Q², formed in the standard E', and provided with a rounded bearing, R², which rests upon the lower wall 105 of the said aperture. The forward end of the lever fits into a seat, S², formed in the carriage G², as shown, while its rear end is countersunk to receive the end of a screw, T², mounted in an arm, U², extending rearwardly from the standard. It is evident, however, that other means than those described may be employed for operating the carriage. The feed-roller is actuated through a ratchet-wheel, V², 110 secured to the shaft K², one end of which projects beyond the side of the carriage, the said ratchet-wheel being engaged by a pawl, W², having its lower end pivoted to an arm, X², formed integral with the bearing B², to which 115 the operating-lever is pivoted, as has been described.

Having described the cutting, mitering, and incurvating mechanisms independently, it now

remains to consider them in their combined relation, and as operated from a common source of power, which in this case is the operating-lever.

5 The mitering-knife is operated directly by the lever Y, as has been explained. The cutting mechanism is operated by said lever through the medium of the frame of the mitering-knife, the said frame engaging and depressing the lever U of the mechanism, and hence operating the knife A thereof. The incurvating mechanism is operated by the lever through the medium of the bearing B', which is oscillated by it to a degree sufficient to successively engage the pawl W² with the teeth of the ratchet-wheel V² and rotate the same and the feed-roller. If desired, the incurvating mechanism may be isolated by removing or throwing back the pawl. By thus combining the cutting, mitering, and incurvating devices in one machine, without interfering with them as distinct mechanisms, their efficiency is preserved and compactness and convenience obtained.

25 It is evident that the several mechanisms are susceptible of some modification as regards minor details of construction, and also that the means for combining them so as to be operated from a common source of power may be varied. I would therefore have it understood that I do not limit myself to the exact construction and arrangement of parts herein shown and described, but hold myself at liberty to make such changes and alterations as 30 fairly fall within the spirit and scope of my invention.

Having fully described my invention, what I claim as new, and desire to secure by Letters Patent, is—

40 1. In a machine for printers' use, the combination, with a lead and rule table and a pivoted lead and rule cutting knife, of a spring-actuated jointed lever connected to the cutting-knife, and an operating-lever, Y, pivoted in the frame of the machine, the parts being arranged substantially as described, whereby the motion of the lever Y actuates the lead and rule cutting mechanism, as set forth.

2. In a machine for printers' use, a reciprocating adjustable support for the mitering-knife, comprising a body, R', mounted upon a pivoted lever, and provided with the interior pivoted bearing, N', and adjusting-screw P', as set forth.

55 3. In a machine for printers' use, the pivoted support for the mitering-knife, comprising the body R', provided with the recess Q' and internal support for the knife, and having the ears G', and a lever, Y, having lips H', and embracing the body R' between the ears G', and pivoted in the frame of the machine, as set forth.

4. A machine for printers' use, having a mitering-knife mounted upon a concaved plate fulcrumed within the frame of the knife, and 65 a screw for depressing the upper ends of the knife and plate to force the edge of the former against the upper wall of the slot in the frame through which it projects, substantially as set forth.

7c 5. A machine for printers' use, having a mitering-table, the outer edge of which is provided with holes located at the points of the mitering-angles, and a rest provided with a spring-actuated pin for engagement with the 75 said holes, substantially as set forth.

6. A machine for printers' use, having a mitering-table, the outer edge of which is provided with holes located at the points of the mitering-angle, and a rest provided with a 80 web and a depending concaved shoulder, in which a spring-actuated pin for engagement with the holes in the edge of the table is located, substantially as set forth.

7. A machine for printers' use, having an adjustable incurvator, constructed substantially as described, and provided with a lip projecting from its inner face and extending into a groove formed in the periphery of the feed-roller, by which the leads and rules are fed 85 forward to the bending-face of the incurvator, substantially as set forth.

8. A machine for printers' use, having an incurvator and friction-roller, constructed and arranged substantially as shown and described, 90 and a removable anti-friction roller, located as shown, substantially as set forth.

9. A combined machine for printers' use, having cutting, mitering, and incurvating mechanisms, and having a lever arranged and 100 provided with means for operating each of the mechanisms, substantially as set forth.

10. A combined machine for printers' use, having cutting and mitering mechanisms, and a lever arranged and provided with means for 105 operating each of the mechanisms, substantially as described.

11. A combined machine for printers' use, having cutting and incurvating mechanisms, and a lever arranged and provided with means 110 for operating each of the mechanisms, substantially as described.

12. A combined machine for printers' use, having mitering and incurvating mechanisms, and a lever arranged and provided with means 115 for operating each of the mechanisms, substantially as described.

In testimony whereof I have signed this specification in the presence of two subscribing witnesses.

CLARK D. FISH.
